UNITED STATES PATENT OFFICE.

JAMES A. HOUSE, OF BRIDGEPORT, CONNECTICUT, ASSIGNOR TO WARNER BROTHERS, OF SAME PLACE AND NEW YORK, N. Y.

ART OF AND MACHINE FOR MANUFACTURING STIFFENING RIBS AND BLADES.

SPECIFICATION forming part of Letters Patent No. 261,717, dated July 25, 1882.

Application filed February 11, 1881. (No model.)

To all whom it may concern:

Be it known that I, JAMES ALFORD HOUSE, of Bridgeport, Fairfield county, Connecticut, have invented certain Improvements in the 5 Art of and Machines for Manufacturing Stiffening Ribs and Blades, of which the following is the specification.

The object of my invention is to connect together a series of bundles of fiber, so as to form 10 a strip or sheet of any required width in which said cords or bundles shall be parallel to the length, and this object I effect by the method and means hereinafter described, and illustrated in the accompanying drawings, in 15 which—

Figure 1 is a side elevation of a machine for forming the described strips. Fig. 2 is an end view; Fig. 3, a sectional elevation, and Fig. 4 a plan thereof; Fig. 5, an enlarged detached 20 view of the parts at the point where the ribs are introduced; Figs. 6 to 9, views illustrating the construction of the strips; and Fig. 10 is a perspective view, showing one of the needles.

25 While my invention may be used for the manufacture of any kind of material or fabric in which parallel longitudinal fibers are connected, it is specially intended to be employed in making "corset-stiffeners" from stiff vegetable 30 fibers—as, for instance, tampico or Ixtle fibers—which may be formed into bundles *a*, so as to constitute stiff continuous ribs, by binding the same together by overlying threads, or may be collected from a mass and separated into bundles just prior to connecting the latter together, 35 as hereinafter described.

The cords or ribs *a*, as, or after being formed of parallel straight fibers, are brought parallel to each other, as shown in Fig. 5, and are then 40 compacted and united into one strip by means of any suitable number of cross-threads, which are woven or sewed, braided, or otherwise combined with the main cords *a* in such manner as to bind the latter all together into one flat 45 continuous piece. Various means may be used for effecting such union of cords or ribs and threads. One which I have found most effective is illustrated in the drawings, which represents a machine whereby the ribs are brought and 50 fed parallel to each other and united by a shut-

tle-thread, *b*, carried by a shuttle, *B*, carrier-thread *b'*, laid by means of a carrier, *C*, and needle-threads *b''*, passed between the various ribs by reciprocating needles *D*.

The frame *A* of the machine is constructed 55 with a race, *x*, for the shuttle *B*, the face-plate *d* of the race being perforated or having transverse tubes *d'* inserted therein for the passage of the ribs or cords *a*, which cross the race above the shuttle to geared feed-rolls *E E*, an 60 intermittent rotation being imparted to the latter by means of a pawl, *d''*, engaging with a ratchet-wheel, *d⁴*, on the shaft of one of the rolls and carried by an arm, *d³*, swinging on said shaft and reciprocated from any moving 65 part of the machine. Any suitable means of adjustment is used whereby the reciprocation of the said arm may be varied to alter the feed.

The needle-frame or arm *F* is secured to or 70 swings on a cross-bar or shaft, *F'*, and is reciprocated by means of a cam, *F²*, on the main shaft *G*, an arm, *f*, attached to the needle-bar or frame, carrying a lug, *f'*, which enters a cam-groove in the side of said cam *F²*.

The needles *D* are carried at the front end of 75 the needle-arm parallel to each other, and set at such an angle that when the arm is down they will lie close to the face-plate *d* in grooves *i* thereof and between the tubes or openings *d'*, the needle-threads *b''* passing from the eyes 80 diagonally across the shuttle-race over the edge of an overhanging plate, *d⁵*, to the fabric, as shown in dotted lines, Fig. 3, so that the shuttle can readily and surely pass between the needles and their threads. Needles of different 85 forms may be used. I have found that most efficient to consist of a thin steel plate, bent or doubled until the sides are nearly in contact, leaving just sufficient space for the passage of a thread, which may therefore be 90 laid easily into the needle, all as shown in Fig. 10.

The needle-threads are carried from bobbins or spools *B³* each through a tension device, *B⁴*, secured at the rear of the frame, so 95 that the required tension can be secured for each separate thread, and from the tension device to a transverse perforated guide-bar, *B⁵*, thence through a perforated plate carried by a take-up lever, *H*, vibrating on the shaft *F'*, 100

and having an arm carrying a stud, n , adapted to a cam-groove in the side of the cam F^2 , such movement being thus imparted to the take-up as will release or tighten the threads, 5 as necessary to secure the desired results.

The thread-carrier C consists of a flat plate, having an eye, m , and spring-lips $m' m'$, and reciprocated on or above the face-plate d by means of a vibrating lever, I , pivoted at the 10 rear end to the frame, and carrying a stud, f^2 , entering a groove in a cam, I^2 , by which the requisite movements are imparted to the lever in proper time. The carrier-thread b' passes from one of the bobbins through one of the 15 tension devices to an eye, g , in the lever I , thence beneath the lips or fingers $m' m'$ to the eye m of the carrier.

The shuttle is reciprocated in the ordinary manner by means of a lever, J , vibrated by 20 means of a cam, J' .

As the cords or bundles a are carried through the channels d' by the action of the feed-rollers, the operations of the different parts of the machine, the needles being up, and the shuttle 25 and carrier both at the same side, Fig. 6, will be as follows: The needles will first descend, carrying the threads between the cords, as shown in Fig. 7, thus presenting the needle-threads for the passage of the shuttle B , which 30 then moves to the left, thereby carrying the shuttle-thread b across the needle-threads below the fabric. The needles then rise, drawing up the shuttle-thread against the under side of the fabric, and holding it by the series 35 of loops of needle-thread which pass between the cords or ribs a . The carrier C then moves to the left, carrying its thread b' over the cords to the position shown in Fig. 8, after which the needles again descend, each needle-thread 40 looping over the overlaid carrier-thread and binding it to the top of the fabric. The needle-threads are then crossed by the shuttle-thread as the shuttle moves to the right, the needles again rise, and the carrier assumes its 45 first position. The continuance of these operations results in firmly binding the cords, ribs, or bundles in a flat fabric or strip, which may be made of any desired length, however short the individual fibers or splints may be, and 50 by properly shaping and arranging the feed tubes or channels d' , and by the use of the requisite number of needles the strip may be made of any desired width or thickness.

A strip or rib of bone or horn may be combined with one or more of the cords of Ixtle fiber, thus forming a compound strip.

In some instances it is desirable to coat or size the material, in which case the ribs a may be passed through a bath before entering the 60 channels d' ; or the strip, after being formed, may be passed through such bath.

It is not necessary, when tampico fibers are used, to bind them into ribs, as they may be fed loosely through the channels d' , and will 65 then be bound together by the operations described. To hold the ribs compactly together,

just as the binding-threads are interlocked they are passed through a channel (just large enough to receive the finished strips) formed between adjustable blocks $n n'$, arranged above 70 the shuttle-race, as shown. These blocks may be adjusted to receive strips of any width.

It will be apparent that arrangements may be made for increasing or decreasing the number of needles D , and for varying the form, 75 number, and arrangement of channels d' .

It is not absolutely necessary to use the thread-carrier C , as the needles or series of ribs may be moved laterally after each upward motion of the needles, so that they will, on again descending, pass each between different ribs than those between which they descended at the previous movement, the needle-threads being locked in such case wholly by the shuttle-thread.

I do not here claim the article produced by 85 the means described, as this was patented to me June 7, 1881.

I claim—

1. The mode described for forming stiffening-strips from stiff fibers, consisting in first bringing the fibers parallel to each other; second, forming bundles or cords of such fibers; third, arranging a series of these bundles or cords parallel to each other; and, finally, uniting them by passing threads across and between 95 the bundles and interlocking the same.

2. The combination, in a machine for forming flat strips from stiff fibers, of a channeled plate for receiving and guiding bundles or ribs formed of said fibers with the channels 100 arranged to maintain said bundles parallel in close proximity, devices for feeding the bundles through said channels, and appliances whereby binding-threads are carried across and between the bundles and interlocked, as set 105 forth.

3. The combination, in a machine for uniting ribs or bundles of stiff fibers, of a channeled plate, feeding appliances, a shuttle, and devices for reciprocating the same, a series of 110 needles, and appliances whereby they are reciprocated between the channels, substantially as set forth.

4. The combination, with the frame A , provided with a shuttle-race and a shuttle, B , 115 of an arm or frame carrying a series of needles, a channeled plate, d , through which to pass a series of ribs, feed-rollers $E E$, a thread-carrier, C , and appliances for reciprocating the shuttle, needle-carrier, and thread-carrier 120 and for operating the feed devices, substantially as set forth.

5. The combination, with the feed-rolls, of the adjustable blocks $n n'$, substantially as set 125 forth.

In testimony whereof I have signed my name to this specification in the presence of two subscribing witnesses.

JAMES ALFORD HOUSE.
